CARL K. JANSEN, FRANK EISBRENNER, AND KASH EISBRENNER, OF TILSONBURG, ONTARIO, CANADA; SAID FRANK EISBRENNER AND SAID KASH EISBRENNER ASSIGNORS TO THE MAPLE LEAF HARVEST TOOL COMPANY, LIMITED, OF TILSONBURG, CANADA.

BLANK FOR FORMING SIX-TINED PITCHFORKS.

No. 832,733.

Specification of Letters Patent.

Patented Oct. 9, 1906.

Application filed January 20, 1906. Serial No. 297,056.

To all whom it may concern:

Be it known that we, CARL K. JANSEN, FRANK EISBRENNER, and KASH EISBRENNER, of the town of Tilsonburg, in the Province of Ontario, Canada, have invented certain new and useful Improvements in Blanks for Forming Six-Tined Pitchforks, of which the following is a specification.

The object of our invention is to devise a blank for the manufacture of six-tined manure-forks, straw-forks, and the like which may be stamped from the stock with a minimum waste of material and in which portions of the blanks from which the tines and shank are rolled are properly spaced and separated in the process of stamping, so that subsequent separation and spacing are avoided; and it consists, essentially, in the construction hereinafter more specifically described and then definitely claimed.

Figure 1 is a plan view showing two complete blanks for a six-tined fork and parts of two others as turned out by the first stamping. Fig. 2 is a plan view of a single blank finished ready for the rolls.

In the drawings like letters of reference indicate corresponding parts in the different figures.

Referring particularly to Fig. 1, it will be seen that each blank comprises a shank portion A, outer tine portions B and C, extending in the same direction as the shank, inner tine portions D and E, extending in the opposite direction to the shank, and intermediate tine portions F and G, extending in the same direction as the tine portions D and E. The die used in stamping the blank is so shaped that as stamped out the shank portion A is separated from the outer tine portions B and C by spaces corresponding exactly in size and shape to the inner tine portions D and E before they are subjected to the second operation, hereinafter described. The inner tine portions D and E are separated from one another by a space corresponding exactly in size and shape to the shank prior to the second operation already referred to. The intermediate tine portions F and G are separated from the inner tine portions D and E by spaces corresponding exactly in size and shape to the outer tine

portions B and C. The tine portions of the shank are integrally connected by the head of the fork H, and it will be noted that the intermediate tine portions F and G are integral with the blank substantially at the juncture between the outer tine portions B and C and the head of the fork. The blanks are thus turned out in the first operation without waste; but before they are in a condition to pass to the rolls a further operation is necessary. By means of an irregular triangular punch a piece of stock is cut away of a roughly triangular shape, as shown at I in Fig. 2. This piece I represents the only waste of material in forming the blank except, of course, the necessary waste at the ends of the stock. The head of the fork H, it will be seen, is now left bent or curved, so as to throw the points of connection a and b of the intermediate tine portions inwardly and forwardly in the direction of the shank.

While we prefer to shape the spacing material or fork-head substantially as the segment of a circle, yet any other shape in which the spacing material would be concave toward the shank would in a large measure answer the purpose of our invention. By thus shaping the head of the fork the waste I is reduced to a minimum, being substantially of the irregular triangular shape shown in dotted lines in Fig. 1 less the space occupied by the point of the shank A of the next blank, which nearly touches the base of the head of the fork. The head of the fork is so curved and proportioned that when straightened out the center and intermediate tine portions are accurately spaced in the positions they occupy in the finished fork.

From the construction described it will be seen that we have devised a blank for forming six-tined forks in which the tine portions and shank portion are all properly separated in the operation of stamping, so that no subsequent splitting or separating is necessary. This gives our blank important advantages over those heretofore employed, in which splitting subsequent to stamping was generally necessary, involving additional operations and also the services of additional men.

What we claim as our invention is—

1. An integral blank for forming pitch-forks and the like, comprising the shank portion; the outer tine portions extending in the same direction as the shank; the inner tine portions extending in the opposite direction; the head of the fork connecting the parts, and cut convex toward the inner tine portions; and intermediate tine portions connected with the blank at the juncture of the head and the outer tine portions, and extending in the same direction as the inner tine portions, substantially as described.
2. An integral blank for forming pitch-forks and the like, comprising the shank portion; the outer tine portions, extending in the same direction as the shank, and separated therefrom by spaces corresponding in shape and size to the inner tine portions; the inner tine portions extending in the opposite direction, and separated by a space corresponding in size and shape to the shank; the head of the fork connecting the parts, and intermediate tine portions connected with the blank at the juncture of the head and the outer tine portions and separated from the inner tine portions by spaces corresponding

in size and shape to the outer tine portions, substantially as described.

3. An integral blank for forming pitch-forks and the like, comprising the shank portion; the outer tine portions; extending in the same direction as the shank, and separated therefrom by spaces corresponding in shape and size to the inner tine portions, the inner tine portions extending in the opposite direction, and separated by a space corresponding in size and shape to the shank; the head of the fork connecting the parts, and cut convex toward the inner tine portions, and intermediate tine portions connected with the blank at the juncture of the head and the outer tine portions, and separated from the inner tine portions by spaces corresponding in size and shape to the outer tine portions, substantially as described.

Tilsonburg, Ontario, January 13, 1906.
